UNITED STATES PATENT OFFICE

BENJAMIN GILOWITZ, OF NEW YORK, N. Y.

SHOE HEEL

Application filed May 15, 1930. Serial No. 452,713.

The invention aims to provide a novel and inexpensive, yet an efficient and desirable shoe heel embodying a rotatable rear section or disk which may be turned to present 5 a new surface for wear after a portion of said section or disk has become worn by continual walking thereon.

With the foregoing in view, the invention resides in the novel subject matter herein- 10 after described and claimed, description being accomplished by reference to the accompanying drawings.

Fig. 1 is a bottom plan view of one form of heel constructed in accordance with the in- 15 vention.

Fig. 2 is a vertical sectional view on line 2-2 of Fig. 1.

Fig. 3 is an elevation of the rotatable sec- 20 tion or disk.

Fig. 4 is an elevation of the heel body.

Fig. 5 is a bottom plan view showing a slightly different form of construction.

Fig. 6 is a top plan view of the structure shown in Fig. 5.

Fig. 7 is a transverse sectional view on line 7-7 of Fig. 6.

In Figs. 1 to 4, the numeral 12 denotes a disk formed of rubber or other elastic ma- 30 terial and adapted to be rotatably mounted upon a shoe. In front of the disk 12, is a flat elastic body 13 having total or partial nail-holes 14 through which to drive attaching nails. Body 13 is provided with a con- 35 cave edge 15 which contacts with the front edge portion of disk 12, and near said edge 15, said body 13 is provided with a suitably shaped slot 16. The edge 15 is provided with an integral detent 17 opposite the slot 16, and the disk 12 is provided with a plurality of circumferentially spaced formations, any of 40 which may co-act with the detent 17 in holding the disk against accidental rotation. The elastic portion 18 between the edge 15 and the slot 16, constitutes means for yieldably holding the detent 17 engaged with the above- 45 named formations of the disk 12, and said portion 18 is formed with an opening 19 into which a nail, awl or the like may be inserted for the purpose of releasing the detent when 50 the disk 12 is to be turned to present a new

surface to wear after one portion has become badly worn at the rear of the heel.

In the present showing, the circumferentially spaced formations above mentioned, are formed by openings 20 of suitable shape 55 near the peripheral edge of the disk 12 and spanned by webs 21 forming portions of said peripheral edge. These webs are suf- 60 ficiently resilient to inwardly spring into the openings 20 and hence when the detent 18 is engaged with one of the webs and the latter is consequently sprung into one of the open- 65 ings 20 as seen at the left of Fig. 1, said disk 12 will be held against accidental rotation. However, by forwardly springing the por- 70 tion 18 to release the detent 17, the disk 12 75 may be adjusted as desired.

In the construction herein illustrated, a flat piece of leather 22 or other appropriate material, is secured upon the upper surface 70 of the body 13 and overlies the disk 12, the latter being rotatably connected with the member 22 by a tubular rivet 23, through 75 which a screw or other fastener may be passed when securing the heel to the shoe.

In Figs. 5, 6 and 7, the structural features 80 denoted at 12^a, 13^a, 14^a, 15^a, 16^a, 17^a, 18^a and 19^a correspond with the portions 12 to 19 above described. The detent 17^a however, is of a different shape and it co-acts with mere notches 20^a in the peripheral edge of the disk 12^a. The disk 12^a is provided with a central opening 23^a to receive an attaching fastener which will also act to rotatably mount said disk.

The disk 12^a and body 13^a are connected 85 unitarily by two strips of canvas or other de- 90 sired material 24 vulcanized or cemented to their upper sides and preferably inset in the latter as illustrated more particularly in Fig. 7. The strip of canvas or the like 24 provides thin webs which tie the parts 12^a and 13^a together at the top of their contiguous edges, in a single unitary structure for easy appli- 95 cation but leave a dividing slit between said edges, and after such application, a knife, a razor blade or the like may be inserted in the slit between the front edge of the disk 12^a and the rear edge of the body 13^a and used 100

to sever said webs, thereby allowing rotation of the disk 12.

While excellent results may be obtained from the details disclosed and they are preferably followed, it is to be understood that within the scope of the invention as claimed, numerous variations may be made.

What is claimed is:—

10 A shoe heel comprising a disk adapted to be rotatably mounted on a shoe, an elastic body in front of said disk adapted for securing to the shoe and having a concave rear edge abutting the front edge portion of said disk, said body being formed with a slot near said 15 concave edge and being provided with a projecting detent on said concave edge opposite said slot, said disk having circumferentially spaced formations any of which may co-act with said detent in holding the disk against 20 accidental rotation, the portion of said body between said slot and said concave edge constituting resilient means for holding said detent yieldably engaged with any of said spaced formations.

25 In testimony whereof I affix my signature,
BENJAMIN GILOWITZ.
